DESIGN FOR A CHILD'S CRAWLER

Edward C. Baus, Cleveland, Ohio, assignor to Edward C. Baus, Cleveland, Ohio, and Everett W. Allen, Cleveland Heights, Ohio, copartners doing business as El-Mar Tube Products Company

Application July 21, 1945, Serial No. 120,865

Term of patent 14 years

(Cl. D34—15)

To all whom it may concern:

Be it known that I, Edward C. Baus, a citizen of the United States and a resident of Cleveland, in the county of Cuyahoga and State of Ohio, have invented a new, original, and ornamental Design for a Child's Crawler, of which the following is a specification, reference being had to the accompanying drawing, forming a part thereof.

In said drawing, Fig. 1 is a side elevational view of a child's crawler, showing my new design; Fig. 2 is a front elevational view thereof; and Fig. 3 is a top plan view.

I claim:

The ornamental design for a child's crawler, as shown.

EDWARD C. BAUS.
